[57] CLAIM

The ornamental design for a cover for beverage serving containers, as shown and described.

DESCRIPTION

FIG. 1 is a top, front, right side perspective view of a cover for beverage serving containers showing my new design in closed position;

FIG. 2 is a top, front, right, perspective view thereof in open position;

FIG. 3 is a right side elevational view thereof;

FIG. 4 is a left side elevational view thereof;

FIG. 5 is a top plan view thereof;

FIG. 6 is a bottom plan view thereof;

FIG. 7 is a rear elevational view thereof; and,

FIG. 8 is a front elevational view thereof;

The broken line showing of a beverage serving container and sign is for illustrative purposes only and forms no part of the claimed design.

FIG. 1

FIG. 2

FIG. 3

FIG. 4

FIG. 5

FIG. 6

FIG. 7

FIG. 8
